Primary Examiner — Katherine Glennon(74) *Attorney, Agent, or Firm* — ScienBiziP, P.C.(57) **CLAIM**

The ornamental design for an alarm clock, as shown and described.

DESCRIPTION

FIG. 1 is a front, right, and top perspective view of an alarm clock, showing our design.

FIG. 2 is a rear, left, and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a partial enlarged view of an area labeled **9** in FIG. 1 comprising a loudspeaker; and,FIG. 10 is a partial enlarged view of an area labeled **10** in FIG. 1 comprising a regulator.

The broken lines shown in the drawings are included for the purpose of illustrating portions of the alarm clock that form no part of the claimed design.

1 Claim, 10 Drawing Sheets(56)
